UNITED STATES PATENT OFFICE

SAM C. JIMOPOULOS, OF ST. LOUIS, MISSOURI, ASSIGNOR OF FOUR-TENTHS TO RALPH NOLEN, OF ST. LOUIS, MISSOURI

BELT

Application filed March 12, 1930. Serial No. 435,195.

This invention relates broadly to supporters for men's trousers and the like, and has more particular reference to a belt.

A primary object of the present invention is to provide a belt having means associated therewith, whereby the buckle may be secured to one end of the belt, in a detachable manner.

A still further object of the invention is to provide a device for securing the belt buckle to one end of the belt, said device being separable and apart from the belt buckle and belt, but capable of being readily secured to the belt and belt buckle for securing the latter to the belt.

Other objects and advantages of the invention will become apparent during a study of the following detailed description, taken in connection with the accompanying drawings, wherein:

20 Figure 1 is a perspective view of the improved belt.

Figure 2 is an elevational view of a buckle attaching device, looking at one side thereof.

Figure 3 is a similar view, looking at the 25 opposite side of the device, to that shown in Figure 2.

Figure 4 is a fragmentary top plan view, for more clearly illustrating the manner of assembling the attaching device to the belt 30 and buckle.

Figure 5 is a perspective view of the hook carrying part of the said attaching device.

Figure 6 is a perspective view looking to the 35 one side of the retaining part of the attaching device.

Figure 7 is a similar view, looking towards the opposite side of the retaining parts of said coupling device.

Figure 8 is a vertical sectional view, taken 40 substantially on the line 8—8 of Figure 1.

With reference more in detail to the drawings, it will be seen that my device comprises a waist encircling belt 5, which is preferably of the reversible type, that is to say, either 45 face of the belt may be worn on the outside. The belt buckle is designated generally by the reference character 6, and this buckle 6 is of the conventional type of belt buckle, now in use.

50 The device, for attaching the belt buckle to

one end of the belt 5 is designated generally by the reference character 7, and said device comprises a loop member formed from a single blank of metal, and comprises a main body portion 8, bent transversely, inwardly 55 from opposite ends thereof, to provide a pair of inwardly directed resilient tongues 9, which tongues 9, at their free inner edges terminate in spaced relation, and form with the body a loop adapted to receive one end 60 of the belt 5, as clearly suggested in Figures 1 and 4. The body portion 8 of said looped member, at one longitudinal side thereof, has formed integrally therewith, a longitudinally extending hook 10, adapted to engage the eye 65 or loop 11 of the buckle 6, as clearly suggested in Figures 1 and 4. When the loop member of the device is arranged on said end of belt 5, it will be noted that the tongues 70 9—9 are disposed on the inner side of the belt. The retaining part of the fastening device, comprises a substantially U-shaped member, formed from a single blank of metal, bent intermediate its ends to provide a pair of co-extensive leg portions 12 and 13, 75 respectively. The leg 12 of the retaining part of the said fastening device, is adapted to be seated in the loop, between the tongues 9 and adjacent section of the belt. On its outer face, the leg 12 is provided with a plurality 80 of penetrating prongs 14, integral therewith, and adapted to penetrate the belt 5 as clearly suggested in Figure 4. Furthermore, at its free end the leg 12 is bent inwardly upon itself to provide a hook 15 extending transversely of the leg and adapted to engage 85 corresponding edges of the tongues 9—9, as also clearly suggested in Figure 4.

The leg member 13 of this securing part extends beyond the hook 15, to abut the edge 90 of the hook 10, as clearly suggested in Figure 4. Obviously, should, for any reason, the eye 11 become disengaged from the hook 10, it is obvious that the extended end of the leg 13, 95 cooperating with the bill of the hook 10, will prevent a complete disengagement of the buckle from the fastening device, unless of course, sufficient pull is exerted upon the buckle for drawing the eye between the contacting edges of hook 10 and leg 13.

From the foregoing, it will be seen that the other end of the belt 5 may be drawn through the buckle in the usual well known manner, and that my fastening device will, in no wise interfere with the passage of said other end of the belt through the buckle.

For receiving that end of the belt passed through the buckle 6, when the belt is worn, I provide inner and outer loop members 16 and 17 respectively. The loop member 16 has one side thereof suitably stitched to one face of the belt 5, as at 18, and the other loop member 17 has one side thereof stitched to the other side of the loop 16 as at 19. Obviously, when the belt is worn as shown in Figure 1, the inner loop 16 will receive that end of the belt passed through the buckle 6.

When the belt is worn on the reverse side, the outer loop 17 will receive said end of the belt passed through the buckle 6, as is apparent.

It is thought that from the foregoing description taken in connection with the accompanying drawings, a clear understanding 25 of the operation, construction, utility and advantages of the invention will be had by those skilled in the art without a more detailed description.

Even though I have herein shown and described the preferred embodiment of my invention, it is to be understood that the same is susceptible to changes fully comprehended by the spirit of the invention as herein described, and the scope of the appended 35 claims.

What is claimed is:

1. In combination, a belt, a buckle therefor, and an attaching device engageable with one end of said belt, and having means for 40 detachable engagement with said buckle for securing the latter to said one end of the belt, a pair of inner and outer loop members circumjacent said belt inwardly from said one end, said inner loop member having one side 45 thereof stitched to said belt, and the opposite side of said inner loop member stitched to an adjacent side of said outer loop member.

2. A belt including in combination two 50 loop members arranged one within the other and disposed circumjacent the belt, the inner one of said loop members having relatively opposite portions secured to the belt and outer loop member respectively.

In testimony whereof I affix my signature.
55 SAM C. JIMOPOULOS.
